UNITED STATES PATENT OFFICE

GEORGE N. MAS, OF LYNCHBURG, VIRGINIA

DESIGN FOR A BOTTLE

Application filed July 22, 1931. Serial No. 40,628. Term of patent 3½ years.

To all whom it may concern:

Be it known that I, GEORGE N. MAS, a citizen of the United States, residing at Lynchburg, Virginia, have invented a new, original, and ornamental Design for Bottles, of which the following is a specification, reference being had to the accompanying drawing, forming part thereof.

The figure is a side elevational view of a bottle, showing my new design.

Only one side of the bottle is shown, the opposite side having substantially the same appearance, although the panel may appear on one face only of the bottle.

I claim:

The ornamental design for a bottle as shown and described.

GEORGE N. MAS.
